UNITED STATES PATENT OFFICE.

THOMAS LLOYD, OF NEW YORK, N. Y.

PYROTECHNIC DEVICE.

SPECIFICATION forming part of Letters Patent No. 708,237, dated September 2, 1902.

Application filed May 31, 1902. Serial No. 109,714. (No model.)

To all whom it may concern:

Be it known that I, THOMAS LLOYD, a citizen of the United States, residing at New York, in the county of New York and State of New York, have invented new and useful Improvements in Pyrotechnic Devices, of which the following is a specification.

My invention relates to improvements in pyrotechnic devices, and has for its main object to provide a simple and inexpensive device, calculated when properly ignited to furnish a vivid imitation of the major eruption of Mont Pelée in the West Indies, and the consequent destruction by fire of the adjacent city of St. Pierre.

Another object of the invention is to so construct the said device that it is susceptible of being compactly folded so as to take up but a minimum amount of space in storage or shipment and is adapted when it is to be used to be quickly and easily unfolded and set up.

With the foregoing in mind the invention will be fully understood from the following description and claims when taken in conjunction with the accompanying drawings, in which—

Figure 1 is a front elevation of my improved pyrotechnic device as it appears when unfolded and set up ready for use; Fig. 2, an end elevation of the same; Fig. 3, a detail rear elevation with the upright tube in which a pyrotechnic compound is placed in section; Fig. 4, an end elevation of the device as it appears when folded, and Fig. 5 a top plan view of the device in its folded condition.

Similar letters of reference designate corresponding parts in all of the several views of the drawings, referring to which—

A is the body of the improved device which in the present and preferred embodiment of my invention is made of one piece of pasteboard or other suitable material and comprises a base *a* and an upright portion *b*. The said base and upright portion being separated by a longitudinal crease *c*, whereby the latter is adapted to be folded on the former after the manner shown in Figs. 4 and 5. The upright portion *b* is shaped in outline and suitably lithographed or otherwise embellished on its face to make it resemble a volcanic mountain—such, for instance, as Mont Pelée of recent fame.

B is an upright tube or receptacle of pasteboard or other material fixedly connected to the back of the body portion *b* and designed to contain a suitable pyrotechnic compound *d*, and C is a stay, preferably of pasteboard, glued to the back of the body portion *b* and having an extended end *e* adapted when the device is set up to be bent into a position at right angles to the said body portion *b*, Fig. 2, so as to prevent the device from tipping over backwardly.

D are strips of readily-combustible material arranged on and connected to the upper side of the base *a* of body A, preferably in such manner that they are enabled to flex or fold on the lines *f*, as shown in Fig. 4. The said strips are preferably of paper prepared with chemicals, so as to enable it to burn rapidly, and they are shaped and embellished, Fig. 1, so as to resemble the various buildings of a city or village.

In practice when it is desired to pack the improved devices for storage or shipment the body portion *b* is folded or swung down into a position adjacent to the base *a*. When this is done, the strips D will assume recumbent positions between the body portions *a* and *b*, and the device as a whole will be rendered very compact, so as to take up but a minimum amount of space in storage or shipment. It will also be observed that when the device is folded it may be conveniently carried in the hand or in the pocket of a coat.

When it is desired to use the device, it is unfolded—*i. e.*, the body portion *b* and the strips D are bent up into positions at right angles to the base *a*, and the extended end *e* of the stay C is bent into a position at right angles to the portion *b* and flush with the base *a*. The device is then set on the ground or on a suitable support and the pyrotechnic compound in the tube B is ignited through the medium of a match applied to a fuse *h* or otherwise. The pyrotechnic compound in the tube B may be of such nature that when it is ignited an initial explosion will take place, and then a shower of fire will be emitted from the tube B like that discharged from the ordinary "Roman candle" in action, or it may be so constituted that fire alone will be discharged from the tube or receptacle B subsequent to the ignition. In either event the

fire will fall upon and ignite the strips D, which will burn rapidly and in consequence the whole will afford a vivid imitation of a volcanic eruption, and a city being destroyed by fire due to such eruption.

Notwithstanding the vividness with which my improved device is adapted to illustrate the eruption of Mont Pelée and the destruction of the city of St. Pierre, it will be observed that the device is extremely simple and inexpensive, and hence may be sold with profit for a very small price.

I have entered into a detailed description of the construction and relative arrangement of parts embraced in the present and preferred embodiment of my invention in order to impart a full, clear, and exact understanding of the same. I do not desire, however, to be understood as confining myself to such specific construction and arrangement of parts, as such changes or modifications may be made in practice as fairly fall within the scope of my claims.

Having described my invention, what I claim, and desire to secure by Letters Patent, is—

1. A pyrotechnic device comprising a body having a base and an upright portion; said upright portion being made to resemble a volcano, and being provided with a receptacle containing a suitable pyrotechnic compound, and one or more strips of combustible material made to resemble a building or buildings, arranged on and rising from the base of the body.

2. A pyrotechnic device comprising a body having a base, and an upright portion flexibly joined to and adapted to fold upon the base; said upright portion being made to resemble a volcano, and being provided with a receptacle containing a suitable pyrotechnic compound, and one or more strips of combustible material made to resemble a building or buildings; said strip or strips being

flexibly joined to and rising from the base of the body, and being adapted, when the upright portion of the body is folded upon the base, to fold between said upright portion and base.

3. The herein-described pyrotechnic device comprising the body formed of a single piece of pasteboard, creased longitudinally at c, and having a base and an upright portion separated by said crease; the said upright portion being made to resemble a volcano, a receptacle arranged on the rear side of the upright portion of the body and containing a suitable pyrotechnic compound, and strips flexibly joined to and rising from the base of the body; the said strips being a paper chemically treated to render them highly combustible, and being made to resemble the buildings of a city or village.

4. The herein-described pyrotechnic device comprising the body formed of a single piece of pasteboard, creased longitudinally at c, and having a base and an upright portion separated by said crease; the said upright portion being made to resemble a volcano, a receptacle arranged in the rear side of the upright portion of the body and containing a suitable pyrotechnic compound, a stay of pasteboard attached to the back of the upright portion of the body and having the extended end e, and strips flexibly joined to and rising from the base of the body; the said strips being of paper chemically treated to render them highly combustible, and being made to resemble the buildings of a city or village.

In testimony whereof I have hereunto set my hand in presence of two subscribing witnesses.

THOMAS LLOYD.
